UNITED STATES PATENT OFFICE.

JOHN J. DANIELS, OF ALBIA, IOWA.

FIRE-ESCAPE.

1,153,200.

Specification of Letters Patent. Patented Sept. 14, 1915.

Application filed March 6, 1915. Serial No. 12,601.

To all whom it may concern:

Be it known that I, JOHN J. DANIELS, a citizen of the United States, residing at Albia, in the county of Monroe and State of Iowa, have invented certain new and useful improvements in Fire-Escapes, of which the following is a specification, reference being had to the accompanying drawings.

My present invention relates to new and useful improvements in fire escapes and has particular reference to the so-called semi-portable fire escape.

The primary object of the invention is to provide a fire escape which consists essentially in a tower, in which an elevator is adapted to be raised and lowered, the tower being mounted on tracks so that it may be moved along the wall of a building to permit the occupants of different rooms and portions of the building to use the elevator.

An object of equal importance with the foregoing is to so construct the tower that a ladder may be attached to one side thereof, making it possible for persons on the ground to mount the tower, without necessitating the operation of the elevator cage.

Another and important object of the invention is to equip the elevator cage with a braking device which may be operated by the occupants of the cage for controlling the speed of the cage during its descent.

Still another object is to equip the winding drum on which the hoisting cable of the elevator cage is wound with a brake band and to connect the brake band with a controlling lever disposed to be operated by a person on the ground, at the foot of the tower.

The above and other incidental objects of a similar nature which will be hereinafter more specifically treated are accomplished by such means as will be illustrated in the accompanying drawings, described in the following specification and then more particularly pointed out in the claims which are appended hereto and form a part of this application.

With reference to the drawings, wherein there has been illustrated the preferred embodiment of this invention, as it is reduced to practice, and throughout the several views of which similar reference numerals designate corresponding parts, Figure 1 is a front elevation showing the fire escape set up for use, adjacent to the wall of a building. Fig.

2 is a side elevation of the fire escape applied to the building; and Fig. 3 is a detail view in side elevation of the elevator cage illustrating particularly the brake mechanism which accompanies the cage.

The preferred embodiment of my invention includes broadly as its essential elements, a tower designated as an entirety by the numeral 10, a cage 11, and a track 12 which is attached to the wall of a building and serves as a support for the upper end of the tower.

The tower 10 includes four uprights or standards 13, 14, 15 and 16. The horizontal braces 17, 18, 19 and 20 which are equi-distantly spaced, are provided to connect the uprights 14 and 15 and similar braces 21, 22, 23 and 24 connect the members 13 and 16. The horizontal braces 25, 25' and 26 connect the standards 13 and 14 and similar braces 27, 27' and 28 connect the standards 15 and 16. A plurality of diagonal braces indicated at 29 may be provided to insure the rigidity and fixed relation of the standards.

The standards and braces, as are the other portions of the tower, are preferably formed of metal, although some other material may be employed, if deemed advisable. Bolts or any other equivalent fastening devices may be employed in securing the braces to the standards. The lower braces 17 and 21 are arranged to bear upon a pair of sills 30 and 31. Fastening devices indicated at 32 are employed in securing the braces 17 and 21 to the sills, as shown in Fig. 1. A pair of additional cross bars 33 and 34 are placed upon the upper faces of the sills to insure the maintenance of these members in parallel spaced relation to each other. The two sills constitute a supporting base for the tower which member is adapted to move over the ground immediately adjacent the wall of the building, indicated conventionally at A in the drawings. Grooved wheels indicated at 35 are provided for the sills so that these members may be moved along tracks B and thus support the tower in proper position adjacent any portion of the building.

From the upper end of the standards 15 and 16, rise a pair of vertical hanger bars 36 and 37 to the upper ends of which is secured a horizontal hanger bar 38 equipped with rollers or grooved wheels 39. These wheels 39 of the hanger bar 38 are adapted to ride along the track 12. This

track is, as previously explained, secured by suitable supporting members to the building adjacent the cornice thereof.

As has been previously set forth it is the 5 primary object of this invention to provide a tower in which an elevator cage is mounted and to design the tower for movement along the wall of the building, so that occupants of the different rooms may all avail themselves 10 of the elevator. It is, therefore, obvious, that it is necessary to provide some means whereby the tower may be mechanically moved along the track. In this connection, I employ the pairs of operating 15 cables 40 and 40' and 41 and 41', which are adapted to be wound upon drums 42 and 43. The members 40 and 41 are respectively attached to the tower, adjacent the upper and lower terminals thereof, as are the members 20 40' and 41'. The drums 42 and 43 are located at opposite ends of the building wall, being journaled on suitable axles and being accompanied with conventional operating 25 handles as shown in Fig. 1. The cables 40 and 41 are passed over the respective pulleys 44 and 45 so that they will run as freely as possible when the tower is being moved along the track. It will be readily apparent 30 that by means of the drums and cables, the tower may be moved along the track in either direction to dispose the elevator to any desired portion of the building.

The elevator cage hereinbefore designated as an entirety by the numeral 11, is of conventional design, including a floor 46, and the vertical corner posts 47. The cage is, of course, mounted for vertical movement and is guided during the raising and lowering operation by means of vertical guide 40 bars 48 and 49 which are secured to the horizontal brace members of the frame. A pair of vertically disposed, spaced, parallel guide plates are provided for each side of the elevator cage, as indicated at 50 and 51. 45 It should be noted that the guide plates are substantially L-shaped in cross section and that the lower terminal of each guide member is secured by a single bolt or equivalent member 52. The upper end of each guide 50 plate is provided with a horizontally disposed slot 53 which is located in that portion of the plate which bears against the wall of the cage. In these slots are disposed the bolts indicated at 53'. It will be obvious 55 that while the guide plates are held against removal from the elevator cage, they are capable of a slight swinging movement, such as will permit them to be tightly or loosely engaged against the guide bars or strips of the tower. The purpose in thus rendering the guide plates capable of movement toward or away from the guide bars of the tower is to permit the use of brake members 60 which may be operated by the occupants of the car. Such a brake member is arranged

at each side of the cage, each consisting of pivoted arms 54 and 55 which are located on opposite sides of the adjacent guide bar and are arranged to bear against the adjacent guide plate. An operating lever 56 is 70 connected by a pair of pivoted links 57 and 58 to the levers 54 and 55. Obviously, the lever 56 may be manipulated to draw the levers or arms 54 and 55 downwardly, causing their ends to engage the pair of guide 75 plates with the resultant frictional contact of these members against the guide bars with such severity as will cause the speed of the cage in its descent to be slackened. It will be noted from Fig. 3 that the lower 80 ends of the brake members or braking shoes 50 and 51 are arranged quite closely adjacent to the web of the guide bar 48, but still not touch this guide bar. The members 54 and 55 have wedging engagement with 85 the flanges of the brake shoes 50 and 51 and thus as the lever 56 is depressed, the levers 54 and 55 are also depressed and gradually force the upper ends of the brake members nearer to the web 48. At this time, the 90 members 54 and 55 are brought into a nearly horizontal position and, therefore, exert a very great leverage upon the members 50 and 51. The members 54 and 55 act, when in a nearly horizontal position, very 95 much like toggle links and thus a comparatively light force applied to depress the lever 56 may be used to exert a very great holding power upon the guide 48. After 100 each descent, the cage is adapted to be again elevated, as soon as the occupants of the cage have stepped out, by means of a weight 59 which is connected to the cage by a cable 60. The cable 60 is arranged to play over a drum or belt wheel 61 which is journaled on an 105 axle or shaft 62 supported on cross beams 63 mounted on the upper end of the tower. The belt wheel 61 is accompanied by a flexible band brake 64, the one end of which is attached to a transverse rod 65 secured to 110 the members 64 and the other end of which is operatively connected to a controlling lever 66 by means of a cable or similar element 67. Obviously, the lever 66 may be manipulated to cause the retarding of the 115 belt wheel by the tightening of the brake band thereabout.

From the foregoing description it will now be apparent that the present fire escape may be easily and quickly moved 120 along the wall of a building to bring the passenger elevator cage within reach of the occupants of any room of the building fronting on the wall adjacent which the tower is arranged. It will also be seen 125 that the elevator cage may be prevented from descending at a dangerous speed by the utilization of the cage brake by the occupants of the car themselves. Furthermore, it will be noted that the operators 130

of the tower may also govern the speed of descent of the cage by means of the braking lever 66.

In many instances, it is found desirable

5 to accompany the tower with a ladder 69.

Preferably this ladder is attached to the side of the tower by bolts or other fastening devices 70, so that it will be rigidly secured.

10 It has been found desirable to place a plurality of springs or equivalent shock absorbing devices on the cross bars 33 and 34 so that the occupants of the cage will not be subjected to severe shock on the landing 15 of the cage.

In reduction to practice, it has been found that the form of this invention illustrated in the drawings, and referred to in the above description as the preferred embodiment, is the most efficient and practical; yet realizing that the conditions concurrent with the adoption of this device will necessarily vary, it is desirable to emphasize the fact that various minor changes in details 25 of construction, proportion and arrangement of parts may be resorted to, when required, without sacrificing any of the advantages of this invention, as defined by the appended claims.

30 What is claimed is:—

1. A fire escape of the character described including an elevator cage, a vertical guide bar, along which the cage moves, a pair of guide plates pivotally mounted at their lower 35 ends on each side of the guide bar, and closely adjacent thereto, and means operable to move the guide plates into frictional engagement with the guide bar, to thereby control the speed of the cage in descending, 40 said means including members pivoted to the cage, each having wedging engagement with one of said guide plates, and manually operable means for shifting the said members into such wedging engagement to force 45 the guide plates against the guide bar.

2. The combination with an elevator cage,

and a vertically disposed guide member therefor, of brake members pivoted at their lower ends upon the frame of the elevator and disposed one on each side of and closely 50 adjacent to the vertical guide, said brake members being adapted to be moved into or out of parallel relation and frictional engagement with the guide, oppositely disposed actuating members pivotally mounted 55 at their outer ends upon the frame of the car and at their inner ends operatively engaging said brake members, and a lever operatively connected to both of said actuating members to simultaneously shift the 60 actuating members toward the horizontal position to thereby shift the brake members into parallel relation and into frictional engagement with the guide.

3. A fire escape of the character described 65 including a tower, and an elevator cage vertically movable therein, guide bars secured vertically within the tower at opposite sides thereof, a pair of guide plates movably mounted at each side of the elevator cage, 70 the individual guide plates of each pair being disposed to bear against opposite sides of the adjacent guide bar, and means operable from within the cage for moving the guide plates into severe frictional engagement with the guide bars for controlling the 75 speed of the cage in descent, said means including a pair of pivoted levers arranged to terminally bear against the outer faces of the guide plates, an operating lever, and 80 link members connecting the operating lever and the first mentioned levers, whereby the terminals of the first mentioned levers may be swung into engagement with the 85 guide plates.

In testimony whereof I hereunto affix my signature in the presence of two witnesses.
